UNITED STATES PATENT OFFICE.

GEORGE T. SMALLWOOD, JR., OF WASHINGTON, D. C., ASSIGNOR OF ONE-HALF TO JAMES HENRY McLEAN, OF ST. LOUIS, MISSOURI.

AUTOMATIC CAR-BRAKE.

SPECIFICATION forming part of Letters Patent No. 284,766, dated September 11, 1883.

Application filed October 5, 1882. (No model.)

To all whom it may concern:

Be it known that I, GEORGET. SMALLWOOD, Jr., a citizen of the United States, residing at Washington, in the District of Columbia, have 5 invented a new and useful Improvement in Automatic Draw-Bar Brakes, of which the following is a specification.

My invention relates to that class of car-brakes in which the various functions of the 10 brake mechanism are performed in consequence of certain movements of the draw-bar, such brakes being known as "draw-bar brakes."

My invention has for its object the production of a brake mechanism which (the train 15 being in motion) shall cause an application of the brakes to occur automatically by simply checking the speed of the locomotive, and, furthermore, to so arrange such mechanism 20 that in case the train is stopped with the brakes off a continued movement of the train in either direction may be produced without causing an application of the brakes; and, finally, to so arrange the said mechanism that 25 in case the train is stopped with the brakes applied a continued movement of the train in either direction may occur without interference from the brakes, such brakes being automatically released by the continued movement. 30

To the above ends my invention consists in the provision of certain mechanical devices, and in the combination of the same, as hereininafter fully set forth.

In order that my invention may be fully understood, I will describe it with reference to the accompanying drawings, in which—

Figure 1 is a side elevation, partly in section, of a car-truck with my invention applied. Fig. 2 is a plan view of a car-truck with my invention applied, the spring-plank being broken away to expose the mechanism beneath it. Fig. 3 is a front view of the truck-beams with the attached mechanism. Fig. 4 is an under side view of the sand-plank, showing the preferred arrangement for operating the slides. Figs. 5, 6, 7, 8, 9, and 10 are illustrations of modifications of devices for moving the slides. Fig. 11 shows the manner of arranging the spring and rod which keep the shoes in their central or normal position. Fig.

12 shows one of the slotted abutments through which the rod for holding the shoe passes. Fig. 13 illustrates the preferred form of the head for the draw-bar extension. Fig. 14 is 55 a transverse section of the same. Figs. 15 and 16 show different forms of slides. Figs. 17, 18, and 19 illustrate the preferred forms of brake-shoes. Figs. 20 and 21 illustrate arrangements for effecting applications of the 60 brakes by hand.

In the said drawings, 3 designates the draw-bar, which is provided with a head, 3*, at its outer end, and arranged to move longitudinally in suitable guides beneath the body of 65 the car. The draw-bar is provided with a buffer-spring, 3^a, which surrounds the said draw-bar, and is confined between two follower-plates, 3^b. These two follower-plates work between two plates, b, one of which is 70 placed above and the other beneath the draw-bar 3. On the inner faces of the plates b, and at each end thereof, are stops b', which limit the longitudinal movement of the said follower-plates 3^b, as shown. A key, 3^c, is secured to 75 the draw-bar just behind the inner follower-plate, 3^b, in order that when the draw-bar is extended in pulling the train the inner follower-plate shall be carried with it. A stop, 3^d, is set so as to be in contact with the upper 80 side of the draw-bar, as shown, for the purpose set forth hereinafter. Between the outer face of the forward follower-plate, 3^b, and the inner face of the draw-head 3*, and surrounding the draw-bar, is a weak spring, 3^e, serving 85 as a cushion between the head and the follower-plate against violent concussion of the two.

1 designates a bar swiveled at its outer end to the inner end of the draw-bar 3, as shown at 90 2, and extending obliquely downward to a connection with a sliding head, 4, presently to be described. This bar I term the "draw-bar extension." The head 4 is preferably wedge-shaped, and when idle rests on the plate 33, 95 secured to the upper side of the sand-plank a.

5 5 designate forked levers, which are pivoted at 6 beneath the said sand-plank, as shown. The upper ends of the levers 5 approach each other above the sand-plank a at a 100 point midway of its length, and in such wise as to be engaged by the head 4 in the manner

hereinafter described. The lower or outer ends of these levers rest upon arms 7, which are jointed or fulcrumed at their inner ends beneath the sand-plank, as shown at 8. There are four of these arms 7 arranged in pairs, one pair being placed in front of and the other pair behind the sand-plank. The outer ends of these arms are each connected at 9°, either directly or through the medium of longitudinal bars, to vertical rods 9, which are connected at 10 to the brake-beams 11. The brake-beams 11 are of peculiar construction, and are secured to the track in such manner as to have free vertical movements while their tendency to horizontal and lateral play is checked. These results are attained by means of guide stirrups or boxes 12, one of which is shown as operating in connection with each brake-beam 11; but more than one will be required in certain cases. As shown, each guide-stirrup is attached directly to the truck-frame on one side and midway of the length thereof, and is provided with a deep depression in its upper part, within which the beam 11 moves, said beam being within the depression at a point about midway of the length of said beam. The two projections or abutments formed by the depression in the stirrup 12 stand against the outer sides of the brake-beam, and are of such height as to guide said beam in its upward movement, which is produced by springs 11^b, interposed between the under side of said beam and the upper side of the truck-frame. The said projections also prevent lateral displacement of the beam. For the purpose of preventing longitudinal movement of the beams 11, stops 11^a, passing entirely through said beam and projecting at each side thereof, are provided, which rest against either side of the said stirrup, as shown. The brake-beams 11 are each arranged to carry as many shoes as there are truck-wheels on either side of the truck, in the present instance a four-wheeled truck being shown. Each beam carries two shoes. In a six-wheeled truck, each beam would carry three shoes, and in an eight-wheeled truck each beam would carry four shoes, &c. At the point of attachment of each shoe the beam 11 is formed with a curved portion, the line of such curvature being on a radius described from the truck-axle as the center. This curved portion serves to guide the shoe in its path of movement as it shifts for the purpose of moving the slides, as hereinafter described.

The manner of attaching the shoes 13 to the brake-beams 11 is shown in Figs. 1 and 17 and 18. The shoe consists of a body, 13, formed with ears 34, between the inner sides of which the curved portion of the beam 11 is placed. Beneath the beam 11, and within the space between the ears 34, is a friction-roller, 35, journaled at its ends in said ears, while above the beam 11 is a pin, 36, seated in said ears and serving to hold the shoe and brake-beam 11 in connection. The wearing-surface of the shoe is formed by a plate, 13^b, of the form shown in Figs. 17 and 18, or as shown in Fig. 19. The

shoes of each brake-beam are connected, so as to move in unison, by a rod, 14, which is connected to each shoe at 15. In order to hold the shoes in their normal position vertically over the axles of the wheels the said rod is passed through vertically-elongated slots 19, (see Figs. 11 and 12,) formed in two abutments, 18, secured to the truck-frame, as shown in Fig. 1. That portion of the rod 14 which lies between the two abutments 18 is reduced in diameter, and is surrounded by a spring, 17, the ends of which rest against the inner faces of two washers, 16, interposed between the said spring and the inner faces of the abutments 18. These washers also rest at their outer faces against the shoulders of the rod 11, formed by the lessened portion, which is surrounded by the spring, and against the inner faces of the abutments 18, so that when the rod moves in one direction it carries one of the washers with it and compresses the spring from one end, and when said rod is moved in the opposite direction it carries the other washer with it, compressing the spring from the opposite end, so that the shoes are acted upon in the same manner by the said spring in either direction of their movement, and are thus kept in their central position.

Attached to the inner side of each of the shoes 13, at 13^a, is one end of a rod, 20, (four of which rods are shown,) which connects at its other end with the upper end of one of four levers, 22, two of which are placed in front of and two behind the truck-timbers to which they are pivoted, as shown at 23. Each of these levers 22 is connected at its lower end to one of four rods, 24, (see Fig. 4,) which are arranged in pairs, and extend horizontally beneath the sand-plank *a* and above the plate 26 to a connection at their inner ends with one or two studs or pins, 25 25, each of which rides in a slot, 26^a, in the plates 26, of which there are two, as shown, and which are secured to the under side of the sand-plank *a*.

To the lower end of each pin 25 is attached one end of a rod, 27, which connects with one of two crank-arms, 28, each of which is secured upon the lower extremity of a vertical shaft, 29, passing up through the sand-plank. There are two of these shafts 29, each of which, at its upper end, is provided with an eccentric, 30, (see dotted lines Figs. 2 and 4,) which works in a slot or socket, 32, in the under side of each of the two slides 31, (see Figs. 2 and 15,) throwing said slides inward and outward, as hereinafter described. I contemplate various modifications of the devices for effecting these inward and outward movements of the slides 31. For instance, in Fig. 5 the parts 27, 28, 29, and 30 are operated by cog and segment gearing. In Fig. 6 the parts 27, 28, 29, and 30 are operated by a link, 24^b, pivoted to 24^b to the sand-plank *a*. In Fig. 7 said parts are operated by a plate similar to that shown in Fig. 4; but the slots are in reversed position to those there shown. In Fig. 8 said parts

are operated by a link, 24^a, acting in a manner opposite to that shown in Fig. 6, said link being provided with a slot, 24^b, and pivoted to the sand-plank, and also controlled in its movements by stops 24^c. In order to cause the pin which works in the slot of the link to begin and continue its movement upon the return of the link from one extreme limit of its movement, I provide converging guide-faces 24^x, 10 against which the pin strikes on the return movement. In Fig. 9 the parts 27, 28, 29, and 30 are operated by bevel-gearing 28^a 29^a. In this figure one of the rock-arms is shown as in its normal position, while the other rock-arm 15 (that on the left) is shown as thrown forward. The parts when in operation never actually assume such relative positions, all movements being similar and in unison, and they are thus shown for purposes of illustration. In Fig. 20, I have represented the rods 27 as placed on top of instead of underneath the sand-plank, as before, and connected directly to the slides 31, in which arrangement the link 24^a is pivoted at its inner end, at 24^c, to the sand-plank, 25 the parts 28, 29, and 30 are dispensed with, and the form of slide shown in Fig. 16 is employed. The slides 31, at their inner portions, are formed with a lateral slope or inclination, and also with an inward longitudinal slope or 30 inclination, both as shown in Fig. 15, the lateral slope being made to correspond with the inclined under side of the head 4, and the longitudinal slope being for the purpose of facilitating the withdrawal of the slides out from 35 under the head 4, while said slides are pressed upon by the head during brake applications. A plate, 33, Fig. 10, is secured to the sand-plank *a* in front of the slides 31, and the head 4 slides upon this plate, raising the inner ends 40 of the arms 5 before passing upon the slides 31, for the purposes hereinafter described.

In order to insure the working of the mechanism in case it is desired to stop the train on a curve, I make the head preferably in a separate piece from the extension 1 and swivel it to the latter. The head 4 is provided with flanges 4^a 4^b, which work in connection with guides 32^a on a platform, 32, secured to the spring-plank *a* in front of the plate 33.

50 In order to provide means for effecting applications of the brakes voluntarily by hand, I employ the arrangements shown in Figs. 20 and 21. In the former arrangement the ordinary hand-brake chain, 39, passes from the brake-staff over a pulley, 37, and thence to a connection with the extension 1. A chain, 39^a, is attached by its inner end to the extension 1, and passes thence to a connection with the hand brake staff. The two chains are coiled 55 around the said staff in opposite directions, so that when the brake-wheel 38 is turned in one direction it will force the head 4 inward, applying the brakes, and when said wheel is turned in the opposite direction the head 4 is drawn outward, releasing the brakes. In the arrangement shown in Fig. 21 a lever, 50, is pivoted at 51 to one of the stringers of the car,

and the brake-chain 39 passes from the upper end of said lever over the pulley 37, and thence to a connection with the extension 1. From 70 the lower end of the lever 50 a chain, 39^a, passes to a connection with the said extension 1, as in Fig. 20. The upper end of the lever 50 moves in a slot, 52, in the platform of the car, said slot being covered by a hinged plate, 75 53. With this arrangement, when it is desired to apply the brakes, the plate 53 is raised and a suitable handle is placed upon the upper end of the lever 50, and the brakes are applied by pushing on the said handle, and they are relieved by a pull thereon, or vice versa. 80

The operation of the automatic brake mechanism is as follows: Supposing the train to be running in the direction indicated by the arrow in Fig. 2, and that it is desired to stop the 85 train, the engineer checks the speed of his engine, and, as a consequence, the cars crowd together end to end. This crowding of the cars, which is due to their acquired momentum, results in forcing the draw-bar 3 inward. The 90 draw-bar first moves the distance from the inner face of its head 3^a to the outer face of the outer follower-plate, 3^b, independently of the draw-bar spring 3^c, or, in other words, without compressing the said spring 3^c. This action is due to the fact that the spring 3^c, interposed between the head 3^a and the forward follower-plate, is practically of no effect as regards 95 the buffer-spring, which is relatively of immensely greater power, the spring 3^c being merely a cushioning-spring to protect the forward follower-plate against the violent concussion of the head 3^a. This independent movement of the draw-bar, acting through the extension 1, which is guided by the stop 3^d, forces the head 100 4 inward, sliding it onto the plate 33 and beneath the levers 5. As the head 4 enters beneath the upper ends of the levers 5, it raises them, depressing their outer ends, and, through the medium of arms 7 and bars 9, depressing 105 the brake-beams 11, and finally bringing the shoes 13 into contact with the tops of the wheels. When the shoes strike the tops of the wheels, they are in their central position, being so held by the rods 14 and springs 17 and 110 the accessories thereof. As soon as the shoes strike the tops of the wheels they are carried with them to the limit of the movement of said shoes. This shifting of the shoes, acting through the medium of bars 20 22 24 and the connections 115 25, 26, 27, 28, 29, and 30, or directly from 24 to 27, as in Fig. 10, throws the slides 31 inward. At the end of the above operations the head 4 continues its inward movement, but now against the action of the spring 3^c. The primary movement described above is necessarily 120 a very powerful one, in order to insure the application of the shoes to the wheels with sufficient force to avoid their slipping over the tires of the wheels, and such movement is consequently made without hindrance from the buffer-spring. The slides 31 being thrown inward, as above described, the head 4 rides 125 upon their inclined upper faces and engages 130

with great power beneath the levers 5, applying the brake-shoes effectively to the wheels, stopping the train. Now, the train having stopped, supposing it is desired to back it, the brakes 5 being applied, the wheels will be at liberty to turn, carrying the shoes with them. As the shoes shift, the slides are now drawn out from beneath the head 4, and it, having now lost their support, drops, allowing the inner ends 10 of the levers 5 to do the same, and the brake-beams 11 are raised by their springs 11^b, lifting the shoes off of the wheels, and also raising the outer ends of the arms 7. The brake mechanism is now in its normal condition, and 15 the cars may be propelled in the direction indicated as rapidly as desired. With the train standing with the brakes applied, after having been running in the direction indicated by the arrow in Fig. 2, supposing the train is to be 20 again moved in the direction indicated by the said arrow, the engine starts and pulls out the draw-bar, and this draws the head 4 out from between the levers 5 and the slides 31. The result is that the brake-beams rise, taking the 25 shoes off of the wheels, and the shoes are instantaneously returned to their normal position by the springs 17 and rods 14, with their accessories, and as the shoes are thus shifted they draw back the slides 31. After this the brake 30 is ready for subsequent action. Supposing the train has been running in the position indicated by the arrow in Fig. 2, and is standing with its brakes not applied, if the train is backed, (in a direction contrary to that indicated by the arrow,) the shoes will be applied as the head 4 is forced in beneath the levers and raises them; but as the wheels are at rest no movement of the slides 31 takes place, and the head 4 drops down in the cavity between 35 the slides 31 and the brakes are not applied. The train is then at liberty to move either backward or forward.

The advantages of this device over others for the analogous purpose are that the shoes 45 are applied to the tops of the wheels, and thus strains on the journals are avoided; also, in case of the pulling out of the draw-bar, it having no direct connection with the brake mechanism will not produce injury to the latter; 50 also, should the mechanism upon one truck fail to work, none of the other mechanisms in the train are disabled.

It is to be understood that I do not confine myself exclusively to the precise construction 55 hereinbefore described; but,

Having thus described my invention, the following is what I claim as new therein and desire to secure by Letters Patent:

1. In an automatic draw-bar brake, the combination, with a draw-bar having a longitudinal movement independent of its buffer-spring, of brake-beams carrying brake-shoes arranged to be shifted longitudinally by contact with the truck-wheels, and a series of devices connected to the said brake-beams and so arranged 65 as to be acted upon by the said movement of the draw-bar, whereby the said movement of

the draw-bar is caused to effect an application of the brakes for the purpose of shifting the brake-shoes. 70

2. In an automatic draw-bar brake, vertically moving brake-beams carrying brake-shoes arranged to be shifted longitudinally by contact with the truck-wheels, movable bearings operated by the movement of the shoes, and 75 connections with the brake-beams for effecting the movement of said beams, in combination with a longitudinally-movable draw-bar, provided with connections acting upon the said movable bearings and engaging with the said 80 brake-beam connections, whereby the movement of the draw-bar is caused to produce a preliminary application of the brake-shoes to the wheels for the purpose of shifting said shoes, and a subsequent effective application 85 of the brake-shoes for braking the wheels. 85

3. In an automatic draw-bar brake, the combination, with a brake-beam, of a series of brake-shoes attached to said beam in such manner as to move longitudinally thereof, and 90 provided with connections which insure simultaneous movements of said shoes and maintain said shoes in and return them to their normal positions, substantially as and for the purposes set forth. 95

4. The draw-bar 3, provided with a supplemental bar, 1, jointed thereto, and having a wedge-shaped head, 4, substantially as and for the purposes set forth. 100

5. A wedge-shaped head arranged to be 100 thrust in by the inward movement of the draw-bar and acting by such movement on the brake-levers, in combination with a shifting-bearing for said head, controlled by the rotation of the wheels, so as to determine the application 105 or non-application of the brakes, as explained. 105

6. The wedge-shaped head 4, connected to the draw-bar through the medium of supplemental bar 1 with a double or universal joint, in combination with guides 32, between which 110 the said head works, substantially as and for the purpose set forth. 110

7. The brake-beams 11, carrying brake-shoes 13, shiftable longitudinally thereon, in combination with a movable bearing or stop, and 115 suitable connections therewith to the said shoes, said bearings serving to determine through the medium of the said connections the application or non-application of the brakes upon the inward movement of the draw-bar, substantially as set forth. 120

8. The combination of the brake-beams 11, shiftable shoes 13, levers 5 and 7, slides 31 31, suitable connections between said slides and shoes, and the draw-bar 3, with its extension 125 1, provided with an attachment for engaging with the said slides and levers, substantially as and for the purposes set forth. 125

9. The combination, with the brake-beams carrying brake-shoes shiftable longitudinally thereon, the system of levers connected to said brake-beams, the movable slides having connections with said brake-shoes, and the draw-bar, with its extension, having an attachment 130

- for engaging with the system of levers, and with the slides, of a hand-brake attachment operating by movements in opposite directions to apply and release the brakes voluntarily.
- 5 10. The combination, with the brake-beams 11, of shoes 13, sliding thereon, and springs 17, operating, substantially as herein set forth, to return the shoes automatically to their normal position when released from the wheels.
- 10 11. The combination, with the brake-beams 11, of shifting-shoes 13, connected thereto by upwardly-projecting lugs or flanges 34, substantially as and for the purposes set forth.
- 15 12. The combination, with the brake-beams 11, shifting-shoes 13, having upwardly-project-
- ing flanges, and the anti-friction rollers 35 to receive the pressure of the brake-beams, substantially as and for the purposes set forth.
13. The combination, with the arms 7 and connections 9, of a break-beam, 11, carrying 20 two or more shoes, and formed with a series of curved sections or portions at the points of attachment of the shoes, said curved sections corresponding in number with the shoes, and being formed each on a curve concentric with 25 the truck-axle.
